JOHN LEWIS TAYLOR AND JOSEPH F. TAPIE, OF SANTA BARBARA, CALIFORNIA

RETORT FOR MINERAL OILS

Application filed March 6, 1929. Serial No. 344,707.

Our invention relates to a retort for mineral oils.

It is an object of this invention to provide a retort for the distillation of mineral oils and the like, in which a film of oil is applied to a moving heated surface, in particular a revolving cylinder internally heated, preferably by electrical means, and disposed within a stationary casing. The lower portion of the revolving cylinder dips into the oil under treatment and a film of oil is thus subjected to a distilling operation which is under the control of the operator. Means are also provided for scraping off residual carbon from the revolving cylinder, which is removed from the apparatus. The retort is so constructed that the distilling operation may be carried on continuously.

The apparatus is intended for the topping of crude mineral oils or the distilling of the same in which the temperatures are high enough to crack the oil or the retort may be used for the distillation of topped oils and the distilling operation may be carried on at sub-atmospheric, atmospheric or super-atmospheric pressure.

Our invention consists of the construction and combination of parts hereinafter described and claimed. Referring to the drawings:

Figure 1 is a front elevation with parts in section, of a retort embodying our invention;

Fig. 2 is a side elevation taken of the right hand end of the apparatus shown in Fig. 1;

Fig. 3 is a vertical cross section taken on the line 3-3 of Fig. 1;

Fig. 4 is a horizontal vertical cross section taken on the line 4-4 of Fig. 3;

Fig. 5 is a side elevation taken at the left hand side of the apparatus shown in Fig. 1.

Referring to the drawings, 1 indicates a valved oil supply pipe, supplying oil from a storage tank (not shown), to a retort indicated as a unit by the numeral 2. The retort comprises an outer stationary shell or casing 3 which may be of any preferred shape but is shown here as a cylinder, the upper part of which is provided with a vapor dome 4 from which leads an outlet vapor pipe 5 to any suitable or preferred condenser, not

shown. 6 is a valved outlet arranged at the bottom of the casing 3. A gauge 7 serves to indicate the level of mineral oil in the casing 3.

A hollow shaft 8 passes through the center of the ends of the casing 3 which are provided with stuffing boxes 9. A hollow metal cylinder 10 closed at each end is fast to the hollow shaft 8. This hollow cylinder 10 is provided internally adjacent the inner wall thereof with electric heating coils 11 of any suitable or preferred construction. Current is supplied to the heating coil 11 by means of conductors 12 and 13 passing through the hollow shaft 8 and terminating in conductor rings 12' and 13' respectively, mounted on insulating plugs 14 and 15 respectively. The conductor ring 12' is in revolving contact with the brush 16 while the conductor ring 13' is brought into contact with the brush 17. The brushes 16 and 17 are connected to a suitable source of electric energy indicated at 18. 19 is a rheostat for controlling the heating element 11.

The cylinder 10 is rotated by means of an electric motor 20 rotating a worm 21 in mesh with a gear 22 fast to the hollow shaft 8. The motor 20 is preferably a variable speed motor so that the speed of rotation of the cylinder 10 may be under the control of the operator.

Means are provided for scraping off and removing either periodically or continuously the residual carbon deposited on the outer periphery of the rotating cylinder 10. The same consists of a longitudinal stationary knife blade 23, the lower portion of which is curved and fastened to the outer shell 3, so as to provide a horizontal longitudinal trough in which a scroll conveyor 24 is disposed. One end of such scroll conveyor 24 projects through one side of the casing 3 and is provided with a gear 25 in mesh with a worm 26 operated by a motor at 27. The other end of the scroll conveyor passes through the opposite side of the shell 3 as at 28.

Operation—Assuming that it is desired to top mineral crude oil, the oil through the supply pipe 1 is introduced into the retort

so that the oil O will occupy the space between the bottom of the casing 3 and the cylinder 10 to a desired level as indicated by the gauge 7. Current is supplied to the heating element 11 within the cylinder 10 and the latter is rotated by means of the mechanism previously described. Since the lower portion of the cylinder 10 dips into the body of the oil O a film or coating will adhere to the periphery thereof and will be quickly distilled during its travel in the rotation of the cylinder 10. For the topping of the oil a low temperature, is sufficient. The topped mineral oil remaining in the retort 2 may now be run off either through the outlet 6 or if desired the temperature may now be raised so as to crack the oil. Any residual carbon is scraped off by the knife blade 23 and conveyed from the apparatus by means of the conveyor scroll 24. The distilling process may be carried on at any pressure desired, either atmospheric, sub-atmospheric or super-atmospheric; the pressure being a function of the condenser apparatus not shown. The speed of rotation of the revolving cylinder 10 may also be regulated as desired. It will be understood that the speed will not only be a function of the diameter of the cylinder 10 but also of the distillation process, the object being to have the film of oil on the cylinder 10 for a sufficient length of time to carry out the particular distillation process.

In the distillation process where destructive distillation is carried on and all the oil is distilled with the exception of the residual carbon deposit which is scraped off and removed by means of the knife blade 23 and the scroll conveyor 24, the process may be continuous. It will be understood also that in case where the distilling process is carried on either above or below atmospheric pressure, provision must be made at the oil inlet and carbon outlet to assure the proper functioning of the retort, preventing the introduction of air into the retort or the escape of vapors therefrom respectively.

We have shown a hinge cover 29, preferably provided with a packing which may be moved over the scroll conveyor outlet 28 so as to prevent access of air to the interior of the shell. The scroll conveyor 24 may be operated intermittently or continuously, having for its operating means an independent motor 27 or the outlet 28 of the scroll conveyor 24 may communicate with an air tight container so that access of air may be prevented to the interior of the shell at all times.

Various changes may be made in the construction and arrangement of parts by those skilled in the art without departing from our invention as claimed.

We claim:

1. A retort for the treatment of mineral oils comprising a stationary casing provided

with a vapor outlet, means for supplying oil to partially fill said casing, a hollow, horizontal shaft, a cylinder spaced from said casing mounted on said shaft and adapted to have its lower portion submerged in said oil, electric resistance coils disposed adjacent the inner periphery of said cylinder, electric conduits leading from said resistance coils and passing through said hollow shaft to a source of electric energy, means for rotating said shaft, a longitudinal knife blade for scraping carbon from said cylinder, and a scroll conveyor for removing the scraped carbon from said casing.

2. A retort for the treatment of mineral oils comprising a stationary casing provided with a vapor outlet, means for supplying oil to partially fill said casing, a rotatable, horizontal cylinder within said casing and adapted to have its lower portion submerged in said oil, means for rotating said cylinder, means for heating said cylinder, and means for removing carbon formed on said cylinder from said casing without said carbon coming in contact with the oil in the lower portion of said casing.

In testimony whereof we have signed our names to this specification.

JOHN LEWIS TAYLOR.
JOSEPH F. TAPIE.
